UNITED STATES PATENT OFFICE.

ADELBERT SAUER, OF PITTSBURGH, PENNSYLVANIA.

HEAT-GENERATOR.

1,369,359.

Specification of Letters Patent. Patented Feb. 22, 1921.

Application filed September 24, 1919. Serial No. 326,044.

To all whom it may concern:

Be it known that I, ADELBERT SAUER, a citizen of the United States, residing at Pittsburgh, in the county of Allegheny and 5 State of Pennsylvania, have invented certain new and useful Improvements in Heat-Generators, of which the following is a specification.

My invention relates to improvements in 10 means for heating fluids, as air, for utilization in any manner desired, as for the heating of buildings, or to the generation of steam in the manner of a boiler. The invention has in view to provide a furnace 15 construction adapted to the combustion of any suitable fuel and the provision of heating chambers and circulating pipes or passages, whereby to bring the fluid to be heated into operative relationship with the 20 gases of combustion and also the waste gases, for the transmission of heat thereto, in a direct, economical and effective manner.

In carrying out my invention, I have so arranged the several circulating passages, 25 etc., so as to also utilize to the fullest degree the latent heat in the outgoing products of combustion.

In the accompanying drawings illustrating 30 one preferred embodiment of the invention,

Figure 1 is a view in front elevation of my improved apparatus, showing it connected with a distributing register or the like;

Fig. 2 is a vertical sectional view on the line II—II of Fig. 1;

Fig. 3 is a horizontal section on the line III—III of Fig. 2;

Fig. 4 is a similar section on the line 40 IV—IV of Fig. 2;

Fig. 5 is a vertical section on the line V—V of Fig. 2;

Fig. 6 is a similar section on the line VI—VI of Fig. 2;

Fig. 7 is a partial sectional view similar 45 to Fig. 2 showing the apparatus designed for superheating steam; and

Fig. 8 is a vertical section on the line VIII—VIII of Fig. 7.

In carrying out my invention I provide 50 an inner combustion chamber or furnace A within an interior shell or wall 2 of suitable sheet or plate metal and a similar outer wall 3, with a continuous intervening air circulation space 4. As shown, the inner and outer walls 2 and 3 respectively and

space 4 are rounded at the top in semi-cylindrical formation, although any other suitable shape may be adopted, whereby to provide for good construction and free circulation. The front portion of the furnace chamber is closed by a similar wall 5 and the rear portion by wall 6 suitably connected as by riveted angle irons, as shown.

Inwardly beyond the rear wall 6 is a 65 transverse partition 7 separating the main interior combustion chamber A from a rear chamber B, into which products of combustion pass from the furnace chamber through one or more circulating openings 8. Said 70 openings 8 are, as shown, located at the lower portion of partition 7, and rear wall 6 is provided with one or more outlet connections 9 leading to a stack or other point of distribution, and preferably provided 75 with a controlling damper 10.

Furnace chamber A may be of any suitable construction, either for combustion of fluid or vaporized fuel, as by means of an oil or gas burner C, like that shown in my 80 prior application Serial No. 321,970, extending inwardly through a suitable opening or openings in the front wall of the furnace chamber, as clearly shown. Grate bars 11 are also provided so that solid fuel, 85 as coal, may be used if desired and the entire lower portion of the chamber is provided with a lining 12 of brick or other suitable refractory material extending upwardly to a sufficient height to properly 90 protect the metal walls.

For the purpose of supplying atmospheric air to the interior of the furnace, it is supplied with a door 13 having suitable dampers for the inflow of atmospheric air, 95 and also, if desired, with a plurality of air supply pipes 14 leading in through the side walls 2 and 3, which may also be provided with controlling dampers, as desired.

The front portion of the space below the 100 furnace chamber, underneath the grate bars 11, is closed off by a transverse partition 15, providing a suitable ash pit 16 having opening and closing door 17 of well known construction. Rearwardly beyond partition 15 105 is an air space 18 extending for the full width of the structure between the outer walls 3 and from partition 15 backwardly to rear wall 6, providing a preliminary heating box or chamber underneath the 110 furnace. For the purpose of introducing atmospheric air thereto from the outside,

a series of vertical conduits 19 extend downwardly through the products of combustion box B, with ample surrounding space for circulation of the gases of combustion, so that cold air entering through conduits 19 is partially heated thereby before passing downwardly into the rear end of chamber 18, and forwardly therethrough.

The ash pit 16 is of substantially the same width as the furnace chamber above the grate bars and is inclosed by supplemental side walls 15' spaced inwardly beyond outer wall 3 whereby to provide the forwardly extending supplemental air heating chambers 20—20, communicating with the main chamber 18. By this means, I utilize the full length of the structure below the furnace chamber for the preliminary air heating cavities 18, 20, 20, which cavities are in open communication upwardly with the continuous space 4 up to and around the top between the main inner and outer walls 2—3.

For the purpose of equalizing pressure between the opposite sides of such chamber, I provide series of transverse pipes or conduits 21 extending through and connecting the inner walls 2, set somewhat closely together and alternating at the upper level with the device of the lower level, as indicated, whereby to effect a very thorough and intimate heating circulation of the gases of combustion throughout the area of the furnace chamber. At the upper portion of the heating chamber are a series of heated fluid supply pipes 22 extending horizontally across from one inner side wall 2 through the other inner and also outer wall 3 to the exterior of the heater, as indicated in Fig. 5, and connected with the supply conduit 23 leading to one or more registers 24 or other suitable utilizing devices. At its rear end the heater is provided with a clean-out door 25 at the base of chamber B, opening out through the rear wall 6 by which the interior may be cleaned from time to time of accumulated ashes or other deposits.

In using the apparatus for the heating of air or other gaseous fluid, the circulation and heating of the air is effected in the manner above described and indicated, the supply of air and its temperature being easily regulated or controlled by the aperture, as will be readily understood. When used or designed for the generation of steam, the conduit 19, spaces 18 and 20, spaces 4, and transverse pipes or tubes 21 will be filled with water up to a suitable level, as indicated by the line a—a, Fig. 5, and the upper portion of chamber 4 and transverse outlet pipes 22 will then be used to contain and convey the produced steam.

It will, of course, be understood that when designed for use as a steam generator, all

of the parts through which the water and steam circulate will be made tight, as is customarily necessary, and in such event, the bottom of chamber 18 may be closed by a bottom plate extending across the entire area of the chamber and tightly connected to the side and end walls thereof. Otherwise, the apparatus may be mounted upon an ordinary cement or other suitable foundation, as indicated in Figs. 1 and 2. 75

In Figs. 7 and 8 I show a modified construction for superheating steam by utilizing the heat of the products of combustion through the outlet chamber b and conduit 9^a to the stack. In such case, the steam or vapor cavity 4^a is connected by pipe 26 with a manifold 27 and a series of vertical pipes 28 extend downwardly through the chamber b to another manifold 29 having a delivery pipe 30 leading to any point 80 of supply. The construction of the furnace chamber and the apparatus is substantially as already described and shown, and the waste gases in circulating around the pipes 28 in their passage through chamber b are thus utilized to very highly superheat the steam produced in the main boiler cavity 4^a. If desired, it is obvious that the pipe 26 may also be connected with any other source of steam supply or generation and the steam may be superheated in the same manner by passing it through the outlet portion of my apparatus, irrespective of its source of generation. 95

In either case, the combustion of the fuel 100 in the furnace chamber and its circulation therethrough and outwardly to the stack, will effect a preliminary and main heating of the fluid in the same manner generally as above described. 105

The construction and operation of the invention will be readily understood and appreciated by those familiar with the art. It is comparatively simple and economical in construction and operation, very highly 110 efficient in the generation of steam and utilization of all of the heat units of the fuel and of the ordinarily waste products of combustion. The invention is very compact in construction, capable of being adapted in any suitable size to various applications, either domestic or industrial, and will be found to meet the requirements of apparatus of this general type. 115

It may be variously changed in detail 120 construction, design, dimensions, or otherwise, by the skilled mechanic or builder, but all such changes are to be considered as within the scope of the following claims.

What I claim is:

1. Heating apparatus of the class described consisting of an inner casing inclosing a furnace chamber, an outer surrounding casing spaced away therefrom and providing an intervening heating and circula- 130

- tion space, transverse circulation conduits opening through the opposite sides of the inner casing and connecting opposite portions of the circulating space, an outlet conduit for products of combustion, and means traversing the furnace chamber for carrying off heated fluid from the heating space whereby fluid carried from said heating space is given a final heating in the furnace chamber before being conducted away.
2. A heating apparatus of the class described consisting of an inner casing inclosing a furnace chamber, an outer surrounding casing spaced away therefrom and providing an intervening heating and circulation space, transverse circulation conduits opening through the opposite sides of the inner casing and connecting opposite portions of the circulating space, air supply conduits for the furnace chamber leading inwardly from the exterior through the outer and inner casings, an outlet conduit for products of combustion, and means traversing the top of the furnace chamber for carrying off heated fluid from the heating space whereby fluid being conducted from the heating space is subjected to a final heating in the furnace chamber.
3. In combination, an inner casing inclosing a furnace chamber, an outer inclosing casing spaced away therefrom providing a circulation space below and at each side of the furnace chamber, an outlet conduit for products of combustion communicating with the furnace chamber, and an air supply conduit extending through the outlet conduit and communicating with the circulation space, and means traversing the top portion of the furnace chamber for carrying off heated fluid from the circulation space at a point near the top thereof.
4. In combination, an inner casing inclosing a furnace chamber, an outer inclosing casing spaced away therefrom providing a circulation space below and at each side of the furnace chamber, an outlet conduit from the furnace, an air supply conduit leading therethrough to the circulation space, transverse circulation conduits connecting the inner casing walls at opposite sides, and outlet conduits leading from suitable points in the circulation space and extending across the upper portion of the furnace chamber and through the inner and outer walls at the opposite side whereby the fluid is subjected to a final heating in the furnace after being conducted from the circulation space and before being conducted away.
5. In combination, an inner casing inclosing a furnace chamber, an outer inclos-
- ing casing spaced away therefrom providing a circulation space below and at each side of the furnace chamber, an outlet conduit from the furnace, an air supply conduit leading therethrough to the circulation space, transverse circulation conduits connecting the inner casing walls at opposite sides, outlet conduits connected with the inner wall at one side and extending across the upper portion of the furnace chamber and through the inner and outer walls at the opposite side whereby the fluid is subjected to a final heating in the furnace chamber after leaving the circulation space, and air supply conduits for the furnace chamber leading into the furnace chamber through both walls.
6. In combination, a rectangular inclosing casing provided with a furnace chamber at its base and an arched top, an outer casing spaced away therefrom providing a heating space having a correspondingly arched top and extending below the furnace chamber level and providing a transverse heating cavity in communication with the heating space, an outlet conduit leading from one end of the furnace chamber for products of combustion, a series of heating pipes leading therethrough adapted to be heated by the circulating products of combustion to give a preliminary heating to the fluid passing into the heating space near the top thereof and through the top of the furnace chamber for conducting the heated fluid from the heating space whereby the fluid is subjected to a final heating in the furnace chamber after leaving the heating space.
7. In combination, an inner casing inclosing a furnace chamber, an outer inclosing casing spaced away therefrom providing a circulation space below and at each side of the furnace chamber, an outlet conduit from the furnace, an air supply conduit leading therethrough to the circulation space, transverse circulation conduits connecting the inner casing walls at opposite sides, and outlet conduits leading from suitable points near the top of the circulation space and extending across the upper portion of the furnace chamber whereby the fluid is subjected to a final heating in the furnace after being conducted from the circulation space, said outlet conduits being alternately arranged on opposite sides of the furnace to remove heated fluid from different sides of the circulation space.

In testimony whereof I hereunto affix my signature.

ADELBERT SAUER.
